UNITED STATES PATENT OFFICE.

GOTTLÖB HAUBER, OF NEW YORK, N. Y.

DESIGN FOR THE SURFACE ORNAMENTATION OF CANES, &c.

SPECIFICATION forming part of Design No. 18,849, dated January 8, 1889.

Application filed September 18, 1888. Serial No. 285,744. Term of patent 7 years.

To all whom it may concern:

Be it known that I, GOTTLÖB HAUBER, of the city, county, and State of New York, have invented a new and original Design for the 5 Surface Ornamentation of Handles of Canes, Umbrellas, and Parasols, of which the following is a specification.

The leading features of this design are a shank in the form of a trunk of a tree, a handle proper in the form of an alphabetical letter above said shank, and a limb extending upward from the trunk and represented as twined around said letter.

In the accompanying drawings, Figures 1, 15 2, and 3 represent side views of handles for canes, umbrellas, and parasols, embodying the leading features of my design.

Similar letters of reference indicate corresponding parts in the different figures. 20 A in the drawings represents the lower part or shank of a handle for a cane, umbrella, or parasol, embodying my design, which shank is in the form of a knurled tree-trunk. The upper part of handle proper, B, is in the shape

of an alphabetical letter and is disposed above 25 the knurled trunk. These parts are represented as united by a limb or limbs, C, which extend upward from the trunk and twine around the letter.

The handle proper is provided with surface 30 ornamentation in the form of leaves stemmed to the limb or limbs C.

I claim—

The design for the surface ornamentation of a handle for a cane, umbrella, or parasol, 35 as herein shown and described, the same consisting of a shank in the form of a tree-trunk, a handle proper in the form of an alphabetical letter disposed above said shank, and a limb represented as extending from one of 40 said parts and twined about the other.

In testimony that I claim the foregoing as my invention I have signed my name in presence of two subscribing witnesses.

GOTTLÖB HAUBER.
